UNITED STATES PATENT OFFICE.

GEORGE M. PAGE, OF HAYDENVILLE, MASSACHUSETTS, ASSIGNOR TO THE HAYDENVILLE COMPANY, OF HAYDENVILLE, MASSACHUSETTS, A CORPORATION OF MASSACHUSETTS.

DESIGN FOR A DRINKING-FOUNTAIN.

44,320.

Specification for Design.

Patented July 8, 1913.

Application filed March 15, 1912. Serial No. 684,004. Term of patent 14 years.

To all whom it may concern:

Be it known that I, GEORGE M. PAGE, a citizen of the United States of America, residing at Haydenville, in the county of Hampshire and State of Massachusetts, have invented a new, original, and ornamental Design for Drinking-Fountains, of which the following is a specification, reference being had to the accompanying drawing, forming part thereof.

The figure is a perspective view of a drinking fountain, showing my new design.

I claim:

The ornamental design for a drinking fountain, as shown.

GEORGE M. PAGE.
